CLAIM

The ornamental design for a cutlery tray, as shown and described.

DESCRIPTION

FIG. 1 is a front, right and bottom perspective view of a cutlery tray, showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view of the cutlery tray, shown in a closed state.

The broken lines shown in the drawings illustrate portions of the cutlery tray that form no part of the claimed design.

1 Claim, 9 Drawing Sheets
